UNITED STATES PATENT OFFICE

ARTHUR C. SCHOLZ, OF MILWAUKEE, WISCONSIN, ASSIGNOR TO SCHOLZ WOODTURNING CO., OF MILWAUKEE, WISCONSIN

DISPLAY FIXTURE

Application filed February 23, 1928. Serial No. 256,359.

My invention refers to display fixtures for general use in displaying samples of goods in retail or wholesale establishments.

Heretofore, this general type of display fixture embodied a pedestal or standard having attached thereto a rest-plate for the support of the articles to be displayed, which rest-plate is usually in hinged connection with the rest-plate, whereby limited angular adjustments can be effected. Owing to the hinged connection, this adjustment could only be effected in a single plane, and thus materially restricted a display, due to the limited means of positioning the rest-plate.

My invention, therefore, contemplates the attachment of any type of rest-plate to the fixture by a simple and economical universal joint connection, whereby said rest-plate or plates can be adjusted at any angle desired.

For example, where a group of rest-plates are supported by a single standard, they may be adjusted at varying angles with relation to each other to more effectually display the articles for sale. It is also to be understood

that the rest-plate or fixture may be varied in form; for example, in displaying shoes, shirts, hats, or the like. The essential feature is that the simple and universal joint connection is formed between any type of rest-plate and any type of standard or spindle.

The specific object of my invention is to provide a universal joint of the type mentioned above, wherein looseness of the joint due to wear or climatic conditions, is eliminated, owing to a peculiar spring take-up mechanism in connection with the joint, whereby the parts of said joint are held firmly in a predetermined adjustment with relation to each other. Briefly, the frictional contact is automatically assured in order that the adjustment of the rest-plate will be held firmly at all times.

With the above and other objects in view, which will appear as the description proceeds, the invention resides in the novel construction, combination and arrangement of parts substantially as hereinafter described and more particularly defined by the appended claim, it being understood that such

changes in the precise embodiment of the herein disclosed invention may be made as come within the scope of the claim.

In the drawings, Figure 1 represents a fragmentary elevation of the upper part of a display fixture embodying the features of my invention, with parts being broken away and in section to more clearly illustrate the structural features; and

Figure 2 is a cross section of the same, this section being taken on the line 2—2 of Figure 1.

Referring by character to the drawing, 1 represents a supporting spindle having a transverse arm 2 extending therefrom, which arm terminates with a vertically disposed sphere 3 having a reduced neck, as best shown in Figure 2.

It is to be understood that the arm 2 may be provided with a similar terminal at its other end. As a matter of fact, the spindle may terminate directly in a spherical portion 3, or there may be one or more arms carrying such spheres for a group of rest plates.

A rest-plate 4 of any desired design is provided and this rest-plate has secured to its lower face by screws, a block 5, which block is provided with a centrally disposed circular aperture 6. This aperture is closed at its upper end by the rest-plate and the lower end thereof is restricted, forming the spherical end, that is, the same diameter as the sphere 3, the same extending below the greater diameter of such sphere.

In assembling the device, the reduced neck 3' of the sphere, which constitutes a part of the sphere, is operable from the arm. It is dropped through the circular opening 6 whereby the sphere forms a wedging contact in connection with a contracted spherical end 90 of the opening.

A friction washer 7 is then dropped into the opening 6 and rested over the sphere or ball 3 and thereafter a sectional coil spring 6' is seated in the opening engaging the washer and lower face of the rest-plate, the same being adapted to exert a constant yielding pressure upon the ball and socket connection when the block is firmly secured to the rest-plate as, for example, by screws.

In practice, the device is preferably composed of wood for ornamental purposes and is tastily finished. Hence, the parts, when all assembled, display no metallic connections or other mechanical features which might mar the artistic effect of the display fixture as a whole. Obviously, however, I may substitute metal for the wood fixture in some cases without departing from the spirit of the invention.

From the foregoing description, it will be seen that by this simple, universal joint connection the rest-plate upon which the goods are placed, can be adjusted at any angle desired and held in such angle securely, due to the constant frictional grip of the walls of the sphere 3 and the lower spherical terminal of the block aperture 6. In instances where the parts are made of wood, or as a matter of fact, even in such cases where the parts are metallic, there is a certain amount of play developed in constantly adjusting the ball and socket connections, which play is readily taken up by the spring to insure sufficient friction to hold the rest-plate in its predetermined position rigidly, irrespective of the load upon the same.

It is understood that I may, in practice, vary the specific details of construction as exemplified in the drawings without departing from the spirit of this invention.

I claim:

In a device of the class described, a rest-plate, a block secured to the rest-plate and having a circular aperture therethrough closed at one end by the rest-plate and having a contracted portion at the other end, a display fixture having a spherical terminal adapted to be fitted into the circular aperture and engage the contracted portion to retain said terminal in the aperture, a flat washer bearing against the spherical terminal and located in said aperture, said washer having an aperture for the reception of a portion of the spherical terminal and a spring tension device interposed between the rest-plate and the washer and adapted to exert frictional pressure against the sphere whereby the rest-plate is rigidly held in any predetermined adjusted position.

In testimony that I claim the foregoing I have hereunto set my hand at Milwaukee, in the county of Milwaukee and State of Wisconsin.

ARTHUR C. SCHOLZ.
